(Cl. D44—26)

To all whom it may concern:

Be it known that I, Giovanni Gaggia, citizen of the Italian Republic, residing at Milan, Italy, have invented a new, original, and ornamental Design for a Combination Pressure Coffee Maker and Dispenser, of which the following is a specification, reference being made to the accompanying drawings, forming part thereof.

Fig. 1 is a front perspective view of a combination pressure coffee maker and dispenser embodying my new design;

Fig. 2 is a rear perspective view thereof;

Fig. 3 is a front perspective view thereof;

Fig. 4 is a side view taken from the left of Fig. 1; and

Fig. 5 is a cross section of the corrugated front plate taken on line 5—5 of Fig. 3.

I claim:

The ornamental design for a combination pressure coffee maker and dispenser, as shown.

GIOVANNI GAGGIA.
